UNITED STATES PATENT OFFICE.

JACOB SCHERFER AND IDA LOUISE KANE, OF CHICAGO, ILLINOIS.

LADY'S UNDERGARMENT OR VEST.

Application filed February 1, 1926. Serial No. 85,166.

Our invention relates to a lady's undergarment or vest, and has for an object to provide a combination undergarment which will take the place of, and will eliminate, the usual brassière, corset, and circular garter.

Other objects will appear hereinafter.

The invention consists in the combinations and arrangements of parts hereinafter described and claimed.

The invention will be best understood by reference to the accompanying drawings forming a part of this specification, and in which,

Fig. 1 is a front elevational view of the invention;

Fig. 2 is a side elevational view thereof;

Fig. 3 is an enlarged fragmentary view of the particular shoulder strap.

The form of construction illustrated comprises a chemise or vest 10 open at the top and bottom and substantially tubular in form, and being provided with shoulder straps 11 fastened to the upper seam 10' of said vest. Each of the straps 11 is arranged so as to be shorter on the inward edge 11' than on the outer edge 11'', and this is preferably done by placing a pleat 12 in the intermediate part of the strap as indicated in the drawings. This construction assures the retention of the straps on the shoulder, and prevents the outward sliding of the

shoulder straps, as is usually the case with the ordinary shoulder straps provided, and especially with the shoulder straps which are 35 constructed in the reverse manner with the outward edge 11'' shorter than the inward edge 11' of said shoulder straps. A draw tape 13 is also provided in the upper seam 10', for contracting the upper end of the 40 vest.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the 50 scope of the appended claim.

Having described our invention, what we claim as new and desire to secure by Letters Patent is:

A lady's undergarment comprising a vest 55 provided with shoulder straps each having its inner edge shorter than the outer edge and including a pleat extending transversely thereof to prevent it from sliding off the shoulder. 60

In testimony whereof we have signed our names to this specification.

JACOB SCHERFER.
IDA LOUISE KANE.
